UNITED STATES PATENT OFFICE.

ERNEST HAUSBERG, OF CHARLES CITY, IOWA.

ELECTRICALLY-OPERATED TYPE-WRITER.

1,200,105.

Specification of Letters Patent.

Patented Oct. 3, 1916.

Original application filed July 25, 1912, Serial No. 711,602. Divided and this application filed January 19, 1914. Serial No. 813,121.

To all whom it may concern:

Be it known that I, ERNEST HAUSBERG, a citizen of the United States, residing at Charles City, in the county of Floyd and 5 State of Iowa, have invented a certain new and useful Improvement in Electrically-Operated Type-Writers, of which the following is a specification.

My invention relates to improvements in 10 electrically operated typewriters of that class in which, by the depression of a key, a selective electromagnet is energized to thereby move a type bar operating device to position to operatively engage a universal 15 operating bar, said universal operating bar being in turn operated by an electropower magnet.

This case is divided out of my companion application filed by me on July 25, 1912, 20 Serial Number 711,602.

The object of my invention is to provide an improved electromagnetic means of simple, durable and inexpensive construction for operatively connecting any one of the 25 series of type bar operating levers to a universal operating bar.

More specifically, it is my object to provide an improved construction in which the 30 selective magnets are mounted on and carried by the type bar operating levers so that in assembling the device a hooked catch for engaging the universal operating bar and a selective electromagnet to operate said hooked catch may both be permanently connected to a corresponding type bar operating 35 lever, and then when the type bar operating levers are assembled within the machine, no other adjustment or arrangement of the selective electromagnets or the hooked catch is 40 necessary.

My invention consists in certain details, in the construction, arrangement and combination of the various parts of the device, whereby the objects contemplated are attained, as hereinafter more fully set forth, pointed out in my claims, and illustrated in the accompanying drawings in which:

Figure 1 shows a side elevation of a typewriter embodying my invention, a part of 50 the typewriter frame being broken away to show the internal construction. Fig. 2 shows a front view of a series of type bar operating levers, and part of the universal operating bar and selective magnets carried

by the type bar operating levers, and Fig. 3 5 shows a detail view illustrating one of the hooked catches and connected parts.

Referring to the accompanying drawings, I have used the reference numeral 10 to indicate generally the frame of the typewriter. 60 On this frame is a sliding carriage 11 of ordinary construction containing the platen 12. The carriage is provided with an ordinary spacing mechanism illustrated generally by the reference numeral 13, which spacing mechanism is automatically operated in a manner to be hereinafter more fully described.

Mounted in the front of the typewriter frame is a series of keys 14, each of which 70 rests upon a spring 15 which, when depressed, engages an electrical conducting bar 16 and closes an electric circuit from said bar through the depressed spring. Mounted upon the frame in semi-circular 75 arrangement, below the platen, is a series of type bars 17, pivotally supported on a curbed shaft 18 and each provided with an upwardly projecting lug 19. Immediately in the rear of and below the shaft 18 is 80 another shaft 20 extending across the machine, and pivoted to this shaft 20 is a series of swinging levers 21. The levers 21, adjacent to the ends, have their upper portions inclined upwardly and inwardly in a 85 direction toward the printing center of the platen, and at the upper end of each of the levers 21 is a link 22 to connect it with the corresponding lug 19. Arranged near the bottom of the typewriter frame, and extended transversely across the frame is a bearing shaft 23 to which is pivoted a series of oscillating levers 24, one for each of the levers 21. At the upper end of each of the levers 21 is a link 25 connecting it with 90 the corresponding lever 21. The links 25 that connect the central levers 21 are attached to the levers 21 near their lower ends, while the links 25 that are connected to the outer levers 21 are connected thereto near 100 their upper ends, as shown in Fig. 1. The arrangement is such that if any one of the levers 24 is moved a certain distance rearwardly at its upper portion, the corresponding type bar will be moved a sufficient distance to strike upon the printing center of the platen and this is done by means of type bars that are all of the same size and shape

and that may be made from the same set of dies.

For the sake of convenience in writing the claims, I shall call the bars 21 the first series of type bar operating levers and the levers 24 the second series of type bar operating levers.

Pivotedly connected to the shaft 23 are the arms 37 which are fixed at their upper 10 ends of the horizontal universal operating bar 38. The upper and lower edges of this bar are beveled or inclined at 39 to coat with the beveled end of the hooked catches 76 to be more fully described.

15 For moving the universal operating bar 38 rearwardly, I have provided an electro power magnet 61 secured to the back of the frame 10. Pivotedly supported below the power magnet are the arms 59 which support the power armature 50 adjacent to the power magnet 61. The link 62 connects the power armature 50 with the universal operating bar 38.

To cause the type bar operating lever 24 25 to be actuated when the universal operating bar 38 is moved rearwardly upon the depression of any one of the keys 14, I have provided the following mechanism: Fixed to each alternate type bar operating lever 24 30 is a bracket 75 having an upwardly extending end 75^a and fixed to each of the type operating bars, between these, I have provided a similar bracket having a downwardly projecting end 75^b. Pivoted to each 35 of the levers 24 carrying an upwardly extending bracket 75^a, is a catch 76 having a downwardly extending hook. Each of the levers 24 carrying a bracket with a downwardly extending end 75^b is provided with a 40 similar catch 76^a having an upwardly extending hook. Each of the catches 76 is provided with a downwardly extending armature 77, and each of the catches 76^a is provided with an upwardly extending armature 77^a. Each of the upwardly extending brackets 75 is provided with an electromagnet 26 in line with the corresponding armature 77 of the catches 76. Each of the downwardly extending brackets 75 is provided 45 with a similar electromagnet designed to operate the armature 77^a of the catches 76^a. The catches 76^a are designed to be moved to their lower limit of movement by means of springs 78 and the catches 76 are 50 designed to be moved to the upper limit of their movement by means of springs 78^a. A stop 20^a is provided on each of the levers 24, to limit the movement of the catches against the action of their respective springs. 55 Each of the electromagnets 26 is connected to a corresponding key 14 through the wires 61 and with the battery by means of the transverse bar 68 and the wire 68^a which form a part of the electric system 60 shown in my companion application above 65.

referred to, the magnets 26 being energized in the same manner by the depression of any one of the keys 14. Thus, it will be seen that when any one of the keys 14 has been depressed, a corresponding electromagnet 70 will be energized which will in turn cause the corresponding catch device to engage the universal operating bar 38, after which the electro power magnet 61 will operate the armature 50 and it in turn will operate the 75 bar 38 through the link 62 and then the levers 24 will be moved rearwardly and the corresponding type bar 17 will be operated through the links 22 and 25 and the lever 21.

80 It is obvious that the design and arrangement of the selective magnets and selective hooks are extremely simple, the construction being compact and having few parts, and the operation of the parts being consequently 85 attended with a minimum of friction, wear and lost motion. Further the parts may be readily and easily assembled or detached.

I claim as my invention:

1. In a device of the class described, the 90 combination of keys, type bars, oscillating levers to operate said type bars, and means for operatively connecting said oscillating levers to said type bars, a universal operating bar, a catch device pivoted to each of 95 said oscillating levers, an armature on each of said catch devices, a selective electromagnet carried by each oscillating lever to move its particular catch device into engagement with the universal operating bar, 100 means for yieldingly holding each of said catch devices out of engagement with the universal operating bar, and means for establishing an electric circuit through a corresponding selective electromagnet when a 105 key is depressed.

2. In a device of the class described, the combination of keys, type bars, type bar operating levers, a universal operating bar, a catch device pivoted to each of said type 110 bar operating levers designed to hook on to said universal operating bar, means for yieldingly holding each of said catch devices out of engagement with the universal operating bar, a selective electromagnet carried by each of the type bar operating levers 115 to move its adjacent catch device into engagement with the universal operating bar, and means for establishing an electric circuit through the corresponding selective 120 electromagnet when a key is depressed.

3. In a device of the class described, the combination of keys, type bars, a first and a second plurality of vertical type bar operating levers, a link for connecting each of 125 the type bar operating levers of the first plurality with a corresponding type bar, a link for connecting each of the type bar operating levers of the second plurality with the corresponding type bar operating levers 130

- of the first plurality, a universal operating bar, a catch device pivoted to each of the type bar operating levers of the second plurality and having an armature thereon, an ⁵ electromagnet carried by each of said levers adjacent to the armature of the catch devices to hook its corresponding catch to the universal operating bar, an electric circuit for each of said magnets having included there-
¹⁰ in one of said keys for operating and closing it, and a spring for each catch to hold it out of engagement with said operating bar.
4. In an electrically operated typewriter, ¹⁵ the combination of keys, type bars, a pivoted lever operatively connected with each of said type bars, a selective magnet and a catch device mounted upon, and carried by, each of said pivoted levers, a universal operating bar, means operated by a selective magnet ²⁰ upon the depression of a key for moving a corresponding catch device into engagement with said universal operating bar, a power magnet, an armature therefor, and means ²⁵ operated by said armature for moving said universal operating bar when a catch device has been moved into engagement with it.
5. In an electrically operated typewriter having selective magnets for moving type ³⁰ bar devices to position to be operated and a power magnet for moving the selected type bar device to printing position, the combination of pivoted levers each operatively connected with a type bar, an armature for the ³⁵ power magnet, a selective magnet and its armature mounted upon each of the said pivoted levers, and means operated by the selective magnet for operatively connecting the pivoted lever with the power armature.
6. In an electrically operated typewriter, ⁴⁰ the combination of keys, type bars, pivoted levers each operatively connected with a type bar, a universal operating bar, a selective magnet mounted upon each of the pivoted levers, an armature for each selective mag- ⁴⁵ net, catch devices each operatively connected with a selective armature and designed to be moved thereby into engagement with the universal operating bar, means for energizing a selective magnet upon the movement ⁵⁰ of a corresponding key, and means for operating the universal operating bar when a catch device has been moved into engagement with it.
7. In an electrically operated typewriter, ⁵⁵ the combination of keys, type bars, pivoted levers each operatively connected with a type bar, a selective magnet and a catch device mounted upon each of the pivoted levers, an electrical connection between each ⁶⁰ of the keys and a corresponding selective magnet, a universal operating bar, means operated by a selective magnet for moving a corresponding catch device into engagement with the universal operating bar, and ⁶⁵ means for operating the said universal operating bar when a catch device has been moved into engagement with it.

Des Moines, Iowa, January 9, 1914.
